The ornamental design for the storage chest, as shown and described.

DESCRIPTION

FIG. 1 is a top perspective view of a storage chest in a closed position;

FIG. 2 is a top perspective view of the storage chest of FIG. 1 in an open position;

FIG. 3 is a top view of the storage chest of FIG. 1;

FIG. 4 is a top view of the storage chest of FIG. 2;

FIG. 5 is a bottom view of the storage chest of FIG. 1;

FIG. 6 is a bottom view of the storage chest of FIG. 2; and

FIG. 7 is a front view of the storage chest of FIG. 1;

FIG. 8 is a front view of the storage chest of FIG. 2;

FIG. 9 is a rear view of the storage chest of FIG. 1;

FIG. 10 is a rear view of the storage chest of FIG. 2;

FIG. 11 is a right side view of the storage chest of FIG. 1;

FIG. 12 is a right side view of the storage chest of FIG. 2;

FIG. 13 is a right side view of the storage chest of FIG. 1; and,

FIG. 14 is a right side view of the storage chest of FIG. 2.

The broken lines in the drawings illustrate features that form no part of the claimed design.
